CLAIM

The ornamental design for a lid assembly, as shown and described.

DESCRIPTION

FIG. 1 is a front perspective view of the lid assembly of the present design positioned within a tumbler;

FIG. 2 is a front perspective view of the lid assembly, removed from the tumbler for clarity of details;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an exploded front perspective view thereof.

The broken lines are shown for the purpose of illustrating environmental subject matter and parts of the article that form no part of the claim.

1 Claim, 5 Drawing Sheets
